Attorney, Agent, or Firm—Virginia C. Majewski

[57] CLAIM

The ornamental design for a saddle attachment for protecting leg and calf, as shown and described.

DESCRIPTION

FIG. 1 is a front elevational view of the saddle attachment for protecting leg and calf, showing my new design;

FIG. 2 is a right side elevational view thereof;

FIG. 3 is the top plan view thereof;

FIG. 4 is a left side elevational view;

FIG. 5 is a rear elevational view thereof; and,

FIG. 6 is a bottom plan view thereof.

The dashed lines of FIG. 1, FIG. 2, FIG. 4 and FIG. 5 represent conventional stitching.
